UNITED STATES PATENT OFFICE.

AUGUST N. RITZ, OF MILWAUKEE, WISCONSIN.

COMBINED MUCILAGE CAP AND SPREADER.

1,407,949.

Specification of Letters Patent. Patented Feb. 28, 1922.

Application filed April 26, 1921. Serial No. 464,724.

To all whom it may concern:

Be it known that I, AUGUST N. RITZ, a citizen of the United States, and resident of Milwaukee, in the county of Milwaukee and State of Wisconsin, have invented certain new and useful Improvements in Combined Mucilage Caps and Spreaders; and I do hereby declare that the following is a full, clear, and exact description thereof.

10 My invention refers to bottle cap closures for original packages for fluid container, such as glue, mucilage or the like. The object of my invention is to provide a simple, economical and convenient cap closure which, 15 with its associated paste distributing elements, is capable of convenient shipping and usage by the consumer. The invention therefore contemplates the use of what is known to the trade as a "crowned cap" unit ar- 20 ranged in connection with other parts to meet the various conditions required of an original package of the type mentioned, whereby said package is hermetically sealed, and is capable of being broken and manipulated 25 to form an integral mucilage or glue dis- tributer, and also a detached mucilage or glue distributer at the election of the user.

With the above objects in view, the invention consists in certain peculiarities of construction and combination of parts, as are hereinafter set forth with reference to the accompanying drawings and subsequently claimed.

In the drawings:

35 Figure 1 represents a sectional elevation of a bottle having a cap closure embodying the features of my invention.

Figure 2 is a partial sectional view of the same with the sealing plug removed and 40 inverted for the purpose of distributing the glue or mucilage contents, and

Figure 3 is a plan view of the same with the sealing plug removed.

Referring by characters to the drawings, 45 A represents any type of bottle for mucilage, glue or the like, which bottle is provided with a mouth terminating with an annular lip B. Fitted to the mouth of the bottle is a crowned cap or shell, having a flat body portion 1 folded down at its edges to form a flange 2 that is crimped, as indicated at 3, in the ordinary manner, the crimped edge of the flange being folded snugly against the annular lip B so as to form a permanent 50 joint. The crowned cap has fitted therein a metal disc 4 that is nested directly against

the inner walls of the cap, being provided with a downturned flange portion 4'. The disc is slightly bowed up at its central points and provided with a plug aperture 5, as 60 shown. The underface of the disc has fitted thereto a thin moist-proof centrally apertured paper wad 6, and between the wad 6 and the upper face of the bottle lip there is snugly fitted a fibre cushion disc 7 which is 65 preferably formed from ground cork or the like, the said cork or fibre disc being apertured in line.

The apertures of the associated parts together form a slight paper tapered opening 70 for the reception of a corresponding tapered plug 8, which plug is provided with a flattened wiper end 8' and a gripping wing 8'' that projects above the bottle. The wiper end is normally immersed within the fluid 75 and when the plug is removed, a certain quantity of the liquid adhering to the wiper end is, under ordinary conditions, ample for the purpose of sealing or coating a body to be glued.

80 As best shown in Figure 3, the central or body portion of the crowned cap is cut away in circular form, and the line of cut extends back to the intersecting edge of the shell body and the downturned flange thereof, 85 whereby a tongue 9 is formed, having a neck portion 9'. This tongue and its neck portion, under shipping conditions, is folded back more or less as shown in Figure 1 of the drawings, and the plug is inserted in the 90 cap unit, as a whole, to form a hermetic seal for the container.

When it is desired to use the glue or mucilage, the plug is removed and its wiper end can be utilized for distributing the 95 mucilage or glue, under certain conditions. If it is desired, however, to utilize a quantity of the paste without interruption, the plug is removed and the bottle or container is inverted, as shown in Figure 2, in which in- 100 105 110 115

cavity, a spoon-like wiper is developed whereby the surplus mucilage or glue is collected within the concave portion and carried along, as the bottle is moved.

5 From the foregoing description, it will be observed that a simple, economical and convenient original package is formed wherein the necessary mucilage or glue distributing elements are conveniently accessible, and the 10 structure, as a whole, is particularly designed for cheapness whereby it can be placed upon the market at a minimum cost.

I claim:

15 In a bottle for mucilage, glue or the like, having a mouth provided with an annular lip; the combination of a closure therefor comprising a flange cap shell permanently crimped about the bottle lip, the cap being

provided with an integral wiping tongue cut from the central body portion of the metal 20 and extending back to the flanged edge thereof, a centrally apertured metallic disc fitted against the inner wall of the cap shell and a centrally apertured fibre disc adjacent the inner wall of the metallic disc for yielding engagement with the lips of the bottle, and a removable tapered plug fitted into the central apertures of the fibre and metal discs, the plug and wiper tongue serving as selective means for spreading the mucilage 25 or glue.

In testimony that I claim the foregoing I have hereunto set my hand at Milwaukee, in the county of Milwaukee and State of Wisconsin.

AUGUST N. RITZ.
